VISIBLE ACCORDION RECORD FILE

Ignatz Hochtheil, New York, N. Y.

Refiled for abandoned application Serial No.
72,046, April 1, 1936. This application August
13, 1938, Serial No. 224,685

1 Claim. (Cl. 129—15)

The invention relates to new and useful improvements in a visible accordion record file. The present application is a refile of my original application filed on April 1, 1936, Ser. No. 72,046.

5 The invention has for an object the construction of a device as mentioned which is characterized by the fact that it is provided with a cover having a central back portion connected with end portions adapted to overlap and form 10 a front portion, and said cover housing an accordion file secured at one end to the inner side of the back portion, and at the other end to the inner side of the bottom or innermost one of said end portions.

15 Still further the invention contemplates constructing the cover of stiff material, and forming several transverse areas (the area separating the back from the front portions) with scoring so as to render it flexible.

20 A still further object of the invention is to construct the accordion file of a plurality of separate collapsible containers attached together at their top portions.

25 Still further the invention proposes to arrange the separate containers in groups of different sizes with portions of the groups projecting to be readily viewable.

30 Still further the invention proposes a provision for adjustable mounting of the groups relative to each other.

Another object of the invention is the construction of a device as mentioned which is simple and durable and which may be manufactured and sold at a reasonable cost.

35 For further comprehension of the invention, and of the objects and advantages thereof, reference will be had to the following description and accompanying drawing, and to the appended claim in which the various novel features of the 40 invention are more particularly set forth.

In the accompanying drawing forming a material part of this disclosure:

Fig. 1 is a perspective view of a device constructed according to this invention.

45 Fig. 2 is a perspective view of another device embodying this invention.

Fig. 3 is an elevational view of the device shown in Fig. 2 in a partially open condition.

50 Fig. 4 is an edge elevational view of the device of Fig. 1 fully open.

Fig. 5 is a fragmentary perspective view of a portion of Fig. 4.

Fig. 6 is a fragmentary sectional view of a portion of a device constructed according to a

modification of the invention, this view being taken on the line 6—6 of Fig. 7.

Fig. 7 is a sectional view taken on the line 7—7 of Fig. 6.

Fig. 8 is a perspective view of a device constructed according to another modification of the invention.

Fig. 9 is an enlarged detail view of a portion of Fig. 6.

Fig. 10 is an enlarged detail view of a portion of Fig. 7.

The visible accordion record file, according to this invention, comprises a cover 10 having a central back portion 10^a connected with end portions 10^b and 10^c. These end portions are adapted to overlap to form a front portion as clearly shown on the drawing. An accordion file 11 is secured at one end 11^{aa} (see Fig. 4) to the inner side of the said back portion 10^a and at the other end 11^{bb} to the inner side of the bottom or innermost end portion 10^c.

In Fig. 1 one form of the invention is disclosed in which the end portions of the cover are held closed by several snap fastener elements 12. These snap fastener elements are mounted on the lower portion of the top or outermost front portion 10^b and coact with complementary snap fastener elements mounted on the outer face of the bottom portion 10^c.

In Fig. 2 another form of the invention has 30 been disclosed in which the means for holding the record file closed comprises a string 14 which is attached on the lower end of the top front portion 10^b of the cover, and which is capable of extending around the entire cover. This string 35 is secured together by tying it at the front as at 14^a.

The accordion file 11 is formed from a plurality of interconnected separate containers 11^a, 11^b, etc., permanently attached together. These 40 containers are individually collapsible and in end elevation when expanded are of triangular shape, as clearly shown in Fig. 4. The apexes are arranged at the bottom. These separate containers are arranged with the shallow container at 45 the front and the deeper containers at the back, as clearly shown in Fig. 4. When thus formed, and the record file is in a partially closed position with the cover open, as shown in Fig. 3, the groups of containers will be clearly visible. 50

Each of the containers, or a group of the containers, are provided with an indicating tab 15. These indicating tabs are made integral with the file walls 11^c and extend above the top edges 11^d thereof. The top edges 11^e of the containers 55

are reinforced with binding strips 16 pasted in position at the outer side of the edges 11^a. The tabs 15 preferably are printed of different colors and arranged in various positions, as clearly shown in Fig. 3. It is thus possible to classify the various containers and use them for holding specific classified data.

A feature of having the accordion file 11 attached as directed resides in the fact that the 10 cover may then be opened completely, as shown in Fig. 4. This is a distinct advantage since the file is stable and cannot be easily spilled. At the same time, the various collapsible containers are exposed so that papers may be inserted or 15 removed therefrom.

In Figs. 6 and 7 and 9 and 10, a modified form of the invention has been disclosed which distinguishes from the prior form in the provision of means for adjusting the relative positions of 20 the containers of a file. The adjacent walls of adjacent pocketed containers are provided with the following mechanism. On one of the walls there are several groups of vertically spaced eyelets 18, 18'. Between these eyelets there are 25 vertical endless bands 19. On the other of the adjacent walls there is a reinforcement strip 20. At certain points the bands 19 are attached to the reinforcement strips 20 by an attaching element 21 held in position on the element 20 by 30 glue or cement 21^a. This attaching element may be string, cement, or the like. With this arrangement it is possible to move the adjacent groups relative to each other within the limitation defined by the bands 19.

Upon the outer face of the wall provided with 35 the eyelets 18 there are flat metal strips 22 stationarily mounted by rivets 23. These flat metal strips are provided with projecting hooks 24. The bands 19 are provided with loops 25 which 40 are adapted to engage the hooks 24. It is thus possible to lock the bands 19 in fixed positions by merely engaging the loops 25 on desired hooks 24.

In Fig. 8 another modified form of the inven-

tion has been disclosed in which a body consisting of a base portion 28 and a hingedly connected cover portion 29 is adapted to encase and house an accordion file 11. These body portions are connected by hinges 30. The portion 29 is provided with a handle 31 by which it may be readily moved. The accordion file 11 is secured or freely mounted within the bottom portion 28. As shown in Fig. 8 the top portion 29 is in a raised position. It may be lowered so as to completely encase the accordion file 11.

While I have illustrated and described the preferred embodiments of my invention, it is to be understood that I do not limit myself to the precise constructions herein disclosed and the 15 right is reserved to all changes and modifications coming within the scope of the invention as defined in the appended claim.

Having thus described my invention, what I claim as new, and desire to secure by United 20 States Letters Patent is:

A visible accordion record file, comprising a cover having a central back portion connecting with end portions adapted to overlap and form a front portion, and an accordion file secured 25 at one end to the inner face of said back portion, and the other end to the inner face of the bottom one of said end portions, and means for securely holding said record file closed, said accordion file comprising a plurality of multi-pocketed 30 containers of different depths, the containers being secured together at the top and said containers being adjustably connected with each other, by reason of superimposed eyelets upon one of the 35 walls of a pair of adjacent containers, bands engaged through said eyelets, reinforcement strips mounted upon the adjacent wall of other said adjacent containers and attached to said bands, said bands being formed with loops and hook elements attached upon one of the walls engageable 40 with said loops to hold the bands in adjusted positions.

IGNATZ HOCHTHEIL.
